the present invention is to provide an improved oar which is extremely light in weight, rugged in construction, and relatively simple to manufacture.

UNITED STATES PATENT OFFICE

2,527,040

METAL OAR

Erich S. Swenson and Emil W. Schwanz, Minneapolis, Minn., assignors to The Flour City Ornamental Iron Co., Minneapolis, Minn., a corporation of Minnesota

Application March 5, 1947, Serial No. 732,398

5 Claims. (Cl. 9—24)

1

Our invention relates to rowing oars and the like and has for its primary object the provision of an oar which is extremely light in weight, rugged in construction, and relatively simple to manufacture.

Another object of our invention is the provision of an oar which can be manufactured from light-weight sheet metals at a relatively low cost.

A still further important object of our invention is the provision of oars which are internally hollow and water-proof.

The above and still further objects of our invention will become apparent from the following detailed specification, appended claims, and attached drawings.

Referring to the drawings wherein like characters indicate like parts throughout the several views:

Fig. 1 is a front elevation of our improved oar;
Fig. 2 is a side elevation thereof;

Fig. 3 is a fragmentary section on an enlarged scale, taken on the line 3—3 of Fig. 1;

Fig. 4 is a fragmentary longitudinal section on an enlarged scale, taken on the line 4—4 of Fig. 1;

Fig. 5 is an enlarged transverse section, taken on the line 5—5 of Fig. 2; and

Fig. 6 is an enlarged transverse section, taken on the line 6—6 of Fig. 2.

Referring with greater particularity to the drawings, the numerals 1 and 2 indicate shell-like matching sections which, when joined together as hereinafter described, form the loom portion 3 and blade portion 4 of our novel oar. Sections 1 and 2 may be constructed from any sheet metal but preferably from some light-weight sheet metal such as aluminum, magnesium, or the like. Each of the shell-like sections 1 and 2 are provided with laterally-projecting flanges 5, which extend continuously around the two sides of the sections 1 and 2 and the blade end thereof and which are fused or otherwise secured together to thereby provide a water-tight seal.

Referring particularly to Figs. 1, 4, and 6, it will be observed that the blade sections adjacent their edges are spaced apart, one from the other, as indicated by the numeral 6, and are inwardly concave at their central portions to provide substantially central abutting engagement one with the other, as indicated by the numeral 7. To impart greater rigidity to the blade, the abutting portions 7 are spot-welded or otherwise secured one to the other. The loom 3 is provided at its intermediate portion with a telescoped axially-extending reinforcing sleeve 8 preferably made

of copper or aluminum, the outer face being rounded to provide a smooth cylindrical surface and the inner face being slightly inwardly flared to provide a shoulder for the blade sections 1 and 2. The sleeve 8 is secured to the sections 1 and 2 by spot-welding or otherwise.

cent their edges and inwardly concave to provide central abutting engagement, one with the other thereof, said blade portions being secured together at their engaging intermediate portions, an axially extended reinforcing sleeve in said loom portion intermediate its ends, a transverse sleeve extending through said reinforcing sleeve and said loom sections, and a handle projecting longitudinally outwardly from the end of said loom portion.

3. A metallic oar comprising opposed matching shell-like sections each having laterally-extended flanges, said sections being secured together at the flanges thereof to form blade and loom portions, the blade portions of said sections being spaced adjacent their flanged edges and inwardly concave to provide substantially central abutting engagement one with the other thereof, said blade portions being secured together at their engaging intermediate portions, an axially-extended reinforcing sleeve in said loom portion intermediate its ends, a transverse sleeve extending through said reinforcing sleeve and said loom sections, and a handle projecting longitudinally outwardly from the end of said loom portion.

4. A metallic oar comprising a pair of opposed matching shell-like sections each having laterally projecting flanges extending continuously around two sides and one end thereof, said sections being secured together continuously at the flanges thereof to form hollow blade and loom portions, the blade portions of said sections being spaced adjacent their flanged edges and inwardly concave to provide substantially central abutting

engagement one with the other thereof, said blade portions being secured together at their engaging intermediate portions, a reinforcing sleeve telescoped in said loom portion intermediate its ends, a transverse sleeve extending through and having locking engagement with said reinforcing sleeve and said sections, and a shank-equipped handle projecting longitudinally outwardly from the open end of said loom portion, the shank of said handle being contained within said loom and having an annular groove, the extreme end of said loom being inturned to provide locking engagement with the annular annular groove in said shank.

5. The structure defined in claim 4 in which the connections between said sections, the connections between said transverse sleeve and said sections, and the connection between said loom portion and said handle are of a water-tight nature.
